UNITED STATES PATENT OFFICE.

GEORGE WINGATE, OF PHILADELPHIA, PENNSYLVANIA.

ROTARY PUMP.

Specification of Letters Patent No. 22,762, dated January 25, 1859.

To all whom it may concern:

Be it known that I, GEORGE WINGATE, of the city and county of Philadelphia and State of Pennsylvania, have invented a new 5 and Improved Rotary Pump; and I do hereby declare the following to be a full, clear, and exact description of the same, reference being had to the accompanying drawing and to the letters of reference marked thereon.

10 My invention consists in a wheel, having any convenient number of chambers, with pistons operated by a cam, in combination with a system of chambers and partitions in an exterior casing, adapted to the said 15 wheel, the whole being constructed and arranged substantially as set forth hereafter, so as to form a rotary pump, which may be applied to any of the purposes for which reciprocating pumps are used.

20 In order to enable others to make and use my invention, I will now proceed to describe its construction and operation.

On reference to the accompanying drawing, which forms a part of this specification; 25 Figure 1, is an exterior view of my improved rotary pump, Fig. 2, a sectional elevation, and Fig. 3, a transverse sectional elevation.

Similar letters refer to similar parts 30 throughout the several views.

A is the base plate and B the exterior casing of the pump, to the opposite sides of which are secured the two plates C and C'. The inside of the casing is bored out slightly 35 tapering, as seen in Fig. 3, so as to be adapted to the reception of the tapering bucket wheel, which will be particularly described hereafter.

Four chambers 1, 2, 3 and 4, are formed 40 in the casing, these chambers being separated from each other by partitions a , a' , a^2 and a^3 , against which the periphery of the bucket wheel bears. The chambers 1 and 4 communicate with each other through a pipe 45 D, and a similar pipe D' forms a communication between the chambers 2 and 3, cocks being connected with the pipes, so as to cut off the communication when required. The two lower chambers 3 and 4 have a branch 50 e, to which a pipe may be coupled, and the upper chambers 1 and 2 have supplementary chambers h , which have each any convenient number of branches for receiving the ends of pipes.

55 A central shaft E passes directly through

the pump, and is arranged to turn in suitable boxes on the standards F and F', which are secured to the base A. Surrounding and fitting close to this central shaft is a sleeve G, which passes through the side C' of the 60 casing, and to which is secured a worm wheel H, into which gears a worm I on a shaft which turns in boxes attached to the base plate A.

The bucket wheel, which is secured to a 65 flange m on the shaft E, has its periphery divided into a number of chambers i by partitions j, and each chamber is furnished with a snugly fitting piston or sliding block n, the position of which within the chamber is 70 controlled by the cam K, which is secured to the sleeve G. On the periphery of the cam is a T formed projection t, grasped by jaws on each piston, the outer edges of the periphery of the cam bearing against the under 75 side of each piston, as seen in Fig. 3. The bucket wheel is, in most respects, similar to that described in the Letters Patent for an improvement in side wheels for steamboats, granted to me on the 22nd day of June. 80 A. D. 1858.

It will be observed that the side C of the casing, at the point where the shaft E passes through it, and the side C', where the sleeve G passes through it, have spaces to be filled 85 with packing material to prevent leaking. It will be also observed, that there is sufficient space between the opposite sides of the casing to allow the bucket wheel, when it has become worn and loose, to be set up 90 by the stud q, which screws into a yoke on the standard F, and bears against the end of the shaft E.

The cam K is double, so that, at every complete revolution of the bucket wheel 95 around the cam, each piston will have made two complete reciprocating movements within its chamber.

The partitions a of the casing are sufficiently wide to cover one of the recesses i 100 of the bucket wheel, and to lap over the partition on each side to a slight extent, as seen in Fig. 2.

Supposing the double cam K to have been moved by the worm I and worm wheel H 105 to the position shown in Fig. 2, in which it is, for the time being, stationary; and supposing the bucket wheel to be turning in the direction of the arrow. The pistons opposite to the partitions a and a^2 will be at the 110

extreme limit of their outward movement, and those opposite to the partitions a' and a'' at the extreme limit of their inward movement, while the pistons opposite to the chambers 1 and 4 will be gradually moving outward and those opposite the chambers 2 and 3 moving inward. The suction pipe must, consequently, communicate with one or the other or both of the chambers 2 and 10 3, and the force pipe with one or the other or both of the chambers 1 and 4. By the time those buckets, which are now opposite the chambers 2 and 3, have arrived opposite to the partitions a' and a'' of the casing, the 15 supply of water, obtained from the suction chambers 2 and 3, will be confined between the partitions and the pistons in their respective chambers, to be subsequently discharged into the chambers 1 and 4, on the 20 further movement of the wheel. It will now be seen, that, as the bucket wheel revolves, the water is constantly flowing into the chambers 2 and 3, and being forced by the bucket wheel out into the chambers 1 and 4, 25 and from thence, through the force pipes, to its destination.

Should the whole capacity of the pump be required for one force and one suction pipe only, the suction chambers 2 and 3 and force chambers 1 and 4 must be made to communicate through their respective pipes D and D', by opening the cocks connected with the said pipes. Should each chamber, however, be used separately and in connec-

tion with independent pipes, the cocks should 35 be closed.

By turning the worm wheel I, the position of the double cam K may be changed, so that the projecting portions of the cam may be opposite to the partitions a' and a'' 40 of the casing, instead of opposite to the partitions a' and a'' , as before. When this takes place and the bucket wheel is turned in the same direction as before, the chambers 1 and 4 will become the suction chambers, and 45 the chambers 2 and 3 the force chambers.

It will be readily seen without further description, that the above described rotary pump may be used as a means of raising and forcing a continuous supply of water by 50 the rotation of the shaft E, and that it may be applied to any of the purposes for which reciprocating pumps are used.

I claim and desire to secure by Letters Patent:

The revolving bucket wheel with any suitable number of pistons operated by the cam K in combination with the exterior casing B its chambers and partitions, the whole being arranged for joint action substantially 55 as and for the purpose herein set forth.

In testimony whereof, I have signed my name to this specification in the presence of two subscribing witnesses.

GEORGE WINGATE.
